(57) **CLAIM**

The ornamental design for a toilet aid tool, as shown and described.

DESCRIPTION

FIG. 1 is a perspective view of a toilet aid tool showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the toilet aid tool where the toilet aid tool is in a folded state; and,

FIG. 10 is an exploded perspective view of the toilet aid tool where the toilet aid tool is in an open state.

The broken lines in the drawings depict portions of the toilet aid tool that form no part of the claimed design.

1 Claim, 10 Drawing Sheets
